UNITED STATES PATENT OFFICE

142,522

DESIGN FOR A BICYCLE FRAME OR THE LIKE

Chester L. Hussey, Belchertown, Mass., assignor to
Savage Arms Corporation, Utica, N. Y., a cor-
poration of Delaware

Application May 7, 1945, Serial No. 119,438

Term of patent 14 years

(Cl. D90—8)

To all whom it may concern:

Be it known that I, Chester L. Hussey, a citizen
of the United States, residing at Belchertown, in
the County of Hampshire, and State of Massa-
chusetts, have invented a new, original, and or-
namental Design for a Bicycle Frame or the Like,
of which the following is a specification, reference
being had to accompanying drawing forming a
part thereof.

In the drawing,
Fig. 1 is a side elevational view of the bicycle
frame, showing my new design;

Fig. 2 is a front view; and

Fig. 3 is a rear view thereof.

I claim:

The ornamental design for a bicycle frame or
the like, as shown.

CHESTER L. HUSSEY.
